UNITED STATES PATENT OFFICE.

BRUCE MURPHY, OF ORILLIA, CANADA.

COLLAR-BUTTON.

SPECIFICATION forming part of Letters Patent No. 714,937, dated December 2, 1902.

Application filed March 18, 1902. Serial No. 98,854. (No model.)

To all whom it may concern:

Be it known that I, BRUCE MURPHY, a subject of the King of Great Britain, residing at Orillia, in the Province of Ontario and Dominion of Canada, have invented new and useful Improvements in Collar-Buttons, of which the following is a specification.

This invention relates to improvements in collar-buttons, and has special reference to 10 that type in which a flat head is adapted to be swung into the same plane as a flat shank on which it is mounted, whereby both may be passed through the buttonhole and the head then swung at right angles to the shank 15 to lie across the buttonhole and to provide an overhanging part under which the tie may be caught, if desired, when the stud is used at the back instead of at the front of the collar.

The invention consists in a construction of 20 a stud of the character described in a simplified form, all as fully set forth in the following specification and carefully pointed out in the claims.

In the drawings forming part of this application, Figure 1 is a sectional elevation of a 25 collar-button embodying my invention, the section on which it is taken being indicated by the line 1 1, Fig. 2. Fig. 2 is a side elevation of Fig. 1 in a plane at right angles to 30 the plane of the latter. Fig. 3 is a plan view looking down on Fig. 2. Fig. 4 is a plan view looking toward the lower side of Fig. 2, a portion of said lower side being broken away. Fig. 5 is a perspective view of a washer forming 35 part of my improved construction, and Fig. 6 is a perspective view of a spring.

The buttons shown in the drawings are all larger than natural size.

The shank of the button is indicated by a 40 and has at one end thereof an annular flange b. The shank is of flattened tubular form, as shown in the drawings, and the extremity thereof opposite to its flanged end is closed, as is clearly shown in Figs. 1 and 3, and in 45 said closed end there is a depression c, extending transversely across it, having a width slightly greater than the transverse dimension of the shank. Centrally of said closed end there is an aperture through which the 50 end of a post d projects, to which is secured in any suitable manner a head or bare, which, preferably, is so formed as to constitute a

proper end piece for the shank a, to the end that when it is swung into parallelism therewith it will appear to be but a continuation 55 thereof. This head e is struck up from sheet metal and is so secured to the post d as to leave a slight concavity at the under side thereof, and the closed end of the shank a is so formed as to be slightly crowning, to the 60 end that when the head e is substantially in parallelism with the shank it will fit over this crowning end thereof and be prevented from readily turning thereon. When, on the other hand, it is swung around into the position 65 shown in Figs. 1, 2, and 3, the edges of said head will ride up on said crowning portions of the end of the shank until the head reaches a position substantially at right angles to the shank, at which point said head will drop 70 into the before-mentioned depression c.

A close contact between the head e and the shank a is maintained by means of a spring f, (which is shown in perspective view in Fig. 6,) which engages the end of the post d, as 75 shown. This spring is supported only by its ends and bridges the hollow shank, to the end that as the head e is swung on the post d the tension of the spring will cause said head either to snap down over the crowning 80 end of the shank when in position to do so or snap in the depression c when in position to enter it.

The completed button is shown in side elevation in Fig. 2, and this view (and Fig. 1) 85 shows the back g put on in the usual manner by being crimped over the flange b on the shank of the button.

It will be observed that a circular washer h is located in the cavity formed by the flange 90 b on one end of the shank of the button. This washer is centrally perforated to allow the post d to move freely endwise therethrough when the head is turned relative to the shank, as described. The purpose of this 95 washer h is primarily to protect the spring f against any undue strain and is slightly cupped, as shown, to such a degree as will permit the spring to be subjected to a degree of flexure which will not cause said spring to 100 set. The spring f obviously cannot be a very rigid one, and therefore if the head e were to be pulled away from the shank the spring might be very easily broken or set without

some means, as said washer, for preventing this.

There are a number of ways in which the proper connection might be effected between the ends of the post *d* and the spring *f*. The preferred manner of constructing these parts is to turn down the end of the post to form a narrow neck *i*, leaving on the end of said post a head *j*, then forming a suitable slot, as *k*, in the spring *f*, which slot is narrower than the head *j* on the end of the post, and then by passing the necked-down portion *i* of the post into this slot in the spring it is seen that the post will thereby be held under endwise tension. The ends of the spring *f*, as shown in Fig. 1 particularly, rest on the borders of the washer *h* at opposite points, the spring bridging the concavity of said washer. This washer is actually a non-essential element, for the ends of the spring might rest at opposite points on the flange *b*, and the button would then operate to all intents and purposes as it does when constructed as shown in the drawings; but, as stated, there is the liability of breaking the spring when the device is constructed without said washer; but this, however, might be provided against in some other way than by the use of the washer. To the end that the spring *f* may operate properly the slot *k* therein extends practically to the center of the spring, at which point the post *d* is suspended thereon, and the opposite end of the spring is likewise slotted, to the end that one portion of said spring may not be much more rigid than another. The washer *h*, being concaved, as shown, serves still another useful purpose, viz: Its surface serves as a guide for the spring *f* when the latter is to be slipped over the necked-down portion of the post *d*, as this operation necessitates the flexure of the spring, which latter is easily accomplished by holding it by one of its ends and pressing the other down against the concaved surface of the washer, whereby the divided ends of the spring are easily slipped into engagement with the portion of the post *d* referred to.

Having thus described my invention, what I claim, and desire to secure by Letters Patent of the United States, is—

1. In a collar-button, the combination with the flattened tubular shank of a button having a crowning closed end, there being a depression in said end transversely thereof, of a post in said shank, a head secured thereto, constituting, when in one position, a continuation of said shank, said head and post being revoluble; a cupped disk located transversely in the shank having an aperture therein for said post, and a flat spring spanning said disk and having a connection with said post. 50

2. In a collar-button, the combination with the flattened tubular shank of a button having a crowning closed end, there being a depression in said end transversely thereof, of a post in said shank, a head secured thereto constituting, when in one position, a continuation of said shank, said head and post being revoluble; a forked spring supported by its ends on the flanged end of the shank, and a head on said post under which the forks of said spring may pass to support the post in operative position. 65

3. In a collar-button, the combination with the flattened tubular shank of a button having a crowning closed end, there being a depression in said end transversely thereof, of a post in said shank, a head secured thereto constituting, when in one position, a continuation of said shank, said head and post being revoluble; a forked spring supported by its ends on the flanged end of the shank, and a head on said post under which the forks of said spring may pass to support the post in operative position, a washer through which the spring-engaged end of the post passes, and whereby the movements of the spring are limited. 75

BRUCE MURPHY.
